UNITED STATES PATENT OFFICE.

OTHO M. OTTE, OF TARENTUM, PENNSYLVANIA.

COMBINED BUTTON ARRANGER AND SAFETY GUARD FOR WRINGERS.

Application filed October 13, 1921. Serial No. 507,559.

To all whom it may concern:

Be it known that I, OTHO M. OTTE, a citizen of the United States, and a resident of Tarentum, in the county of Allegheny and 5 the State of Pennsylvania, have made a new and useful invention in Combined Button Arrangers and Safety Guards for Wringers, of which the following is a specification.

This invention relates to clothes wringer 10 attachments.

The buttons on clothes when run through wringers as ordinarily operated are liable to be either torn from the clothes or broken by the pressure rolls of the wringer because 15 of the fact that a large proportion of them are forced to enter the pressure rolls at an improper angle with relation to the line of travel of the clothes through the rolls. I have found that if the buttons on clothes 20 are laid flat before entering the rolls, the tendency to tear them from the clothes or to break them is reduced to a minimum, and an object of this invention is to provide 25 means for automatically adjusting or arranging the buttons on clothes prior to their entrance between the wringer rolls.

A further object is to provide a combined button adjuster and safety guard for clothes wringers.

These, as well as other objects which will readily appear to those skilled in this particular art, I attain by means of the device described in the specification and illustrated in the drawings accompanying and forming 35 part of this application.

In the drawings, Figure 1 is a side view in elevation of a wringer of ordinary construction with a device embodying this invention applied thereto. Fig. 2 is a sectional view taken on line 2-2 of Fig. 1, looking in the direction of the arrows. Fig. 3 is a diagrammatic vertical sectional view of the attachment. Fig. 4 is a fragmentary view in section of a modified form of the 40 attachment and Fig. 5 is a fragmentary view partially in plan and partially in section of the modification.

In the simple form of device shown in Fig. 1 two supporting brackets 7-7, preferably stamped from sheet metal, are mounted so as to slide on support pins 8-8 having wood screw ends 9 screwed into the end posts 10 of a clothes wringer.

The wringer may be of any ordinary construction, either hand or power operated, and ordinarily will consist of the end posts,

slotted to receive bearing blocks 11 within which the compression rolls 12 and 13 are journaled. These wringers are preferably provided with compression springs 14, a 60 follower 15 and a compression screw 16.

Each of the brackets 7 as has been said, is preferably stamped from sheet metal and each is provided with a guide bracket 17 riveted to the body portion of the bracket 65 and with an end flange 18. The guide bracket and end flange are pierced to receive pin 8 and with said pin provide a 70 slideable mounting between flange 18 and a washer 19 which lies against end post 10 of 75 the wringer. A coil spring 20 surrounds support pin 8. These springs, there preferably being four in number, for each device, tend to yieldingly hold the brackets toward the limit of outward movement or 80 away from the wringer and in contact with stops 21 carried by support pins 8. Each of the brackets 7 is provided with upper and lower elongated guide slots numbered 22 and 23 respectively and the trunnions 24 85 of upper and lower idler rollers 25 and 26 respectively are mounted therein. Tension springs 27, one for each bracket, have their ends looped over the trunnions as shown in Fig. 1 and yieldingly hold the rollers 25 and 26 toward the lower and upper limits 90 respectively of their travel in the elongated slots 22 and 23.

An endless or tubular conveyor 28 formed of any suitable textile material passes 90 around compression roll 13 and roller 26 and a similar conveyor 29 passes around upper compression roll 12 and idler roller 25. Springs 20 tend to keep the endless conveyors taut. 95

As the wringer is operated and the compression rolls revolved, the adjacent runs of the conveyor will move in the direction of arrow X, Figures 1 and 3, and carry any clothes or other material toward and 100 through the compression rolls of the wringer. Springs 27 for yieldingly holding the idler rollers for the conveyors in normal position allow the entrance opening between the outer ends of the conveyors to accommodate varying quantities or amounts 105 of material.

The superposed conveyors are so arranged that their adjacent runs which pass through the rolls converge from the variable 110 opening between idler rollers 25 and 26 to the roll contact line where they are

pressed into engagement one with the other by the pressure rolls. The conveyors thus form yielding means for carrying the material to the compression rolls and for yieldingly and progressively compacting the same so as to lay the buttons on the clothes in a substantially horizontal plane, thus ensuring an easy passage through the rolls without tearing the same from the clothes to which they are attached and thereby reducing to a minimum the breakage of buttons occasioned by improper entrance between the rolls.

It is now customary in using power wringers to operate the same in either direction and in Figs. 4 and 5, I have illustrated a modification of this invention as applied to a wringer such as a power wringer, where it is desired to operate the same in both directions. In this form of device, support plates 40, one for each side of each end post 41 of the wringer is provided, and each of these plates is preferably provided with an upper support pin 42 and a lower support pin 43.

Two independently slidable bearing brackets are provided for each support plate. Bracket 44 preferably stamped from sheet metal, so as to have a top flange 45 and an end flange 46 has two ears 47 struck up from the body of the bracket and these are pierced with aligned holes to receive support pin 43. Upper bracket 48 is provided with a bottom flange 49 having elongated slots 50 through which rivets carried by the top plate of bracket 44 extend. Bracket 48 is also provided with an end plate 51 pierced to receive support pin 42.

Coiled springs 52 and 53 surround support pins 43 and 42 respectively and yieldingly force brackets 48 and 44 toward the limit of their outward movement.

Springs 52 for the lower conveyor are preferably stiffer than those for the upper conveyor so as to compensate for the weight of the wet clothes.

Similar brackets are carried on opposite sides of each wringer end post as before said and both upper brackets 48 are provided with a bearing slot 54 adapted to receive a trunnion 55 of idler roller 56. The bracket above slot 54 has a groove 57 pressed therein as shown in Fig. 5, so as to serve as a guide for guiding trunnion 55

to its slot 54. Idler rollers 56 are yieldingly held toward the bottom of bearing slot 54 by means of a C spring 58, at one end secured to the bracket and at the other hooked over trunnion 55.

Each bracket 44 is provided with a bearing slot 59 which stands at an angle to the vertical, and bracket member 44 has a groove 60 pressed therein for the reception of trunnion 61 of idler roller 62.

An endless conveyor 63 formed of suitable tubular textile material passes around idler rollers 62 and lower compression roll 64 of the wringer while a similar endless conveyor 65 passes around idler rollers 56 and upper compression roll 66 of the wringer. The upper endless conveyor 65 is materially shorter than the lower endless conveyor as shown in Figs. 4 and 5. For this reason, those portions of the lower conveyor which project beyond the ends of the upper conveyor form moving tables or shelves upon which the clothes may be placed for entrance into the device.

Having thus described my invention, what I claim is:—

1. The combination with the compression rolls of a wringer, of a pair of endless belts for conveying material to said compression rolls and means for yieldingly supporting the outer reaches of each of said belts.

2. The combination with the compression rolls of a wringer, of a pair of endless belts adapted to convey material to said rolls, a roller adapted to support the outer reach of each belt, means for yieldingly supporting said rollers so as to permit vertical movement thereof and means for pressing said rollers outwardly to tension said belts.

3. The combination with the compression rolls of a wringer, of a pair of endless belts adapted to convey material to said rolls and to simultaneously yieldingly arrange and progressively compact the material, a roller for supporting the outer reach of each of said belts, brackets adapted to support said rollers so as to permit vertical movement thereof and means for pressing said brackets outwardly so as to tension said belts.

In testimony whereof, I have hereunto subscribed my name this 8th day of October, 1921.

OTHO M. OTTE
